(57) **CLAIM**

The ornamental design for a wall bracket, as shown and described.

DESCRIPTION

The nature of this product is as a bracket for attaching a bottle or container to a wall for the purpose of dispensing solutions.

FIG. 1 is a right, front, perspective view of a wall bracket showing our new design;

FIG. 2 is a right side elevational view thereof, the left side elevational view thereof being a mirror image of the right shown;

FIG. 3 is a front elevation view thereof;

FIG. 4 is a top plan view thereof; and,

FIG. 5 is a bottom plan view thereof.
